WALL PLATE FOR FURNACES

Edgar B. Tolman, Jr., Chicago, Ill.

Application June 21, 1934, Serial No. 731,622

9 Claims. (Cl. 72—101)

The invention relates to wall plates, and more particularly it relates to wall plates providing anchor members for brick lining walls for furnaces, ash pits and the like.

5 The use of wall plates for this purpose is well-known, but such plates as heretofore constructed are not adapted for use with brick walls of standard construction, since their anchorage requires that some or all of the brick be of special 10 construction or that they be arranged in some special manner.

It is an object of the invention to provide wall plates of the kind described having anchor members so arranged and constructed that brick of 15 standard sizes and construction may be laid perpendicular to the wall plate to form a wall anchored to the plates and providing a smooth exposed surface completely concealing the anchor members. This desirable result is accomplished 20 by providing wall plates adapted to be assembled to form a wall either vertical or inclined and having anchor members projecting at right angles from the face of the plate adjacent the wall. The anchor members are arranged in horizontal 25 and vertical rows and so constructed as to occupy the mortar spaces adjacent the contiguous ends of the brick with each anchor member providing lateral projections upon which the ends of the contiguous brick are positioned. The anchor 30 members are also arranged in vertical rows in such a manner that each horizontal layer of brick breaks joints with the brick immediately above and below.

Another object of the invention is the provision 35 of improved wall plates of the kind described, adapted to form a unit of an assembly providing a backing for a brick wall, said plates each providing a plurality of projecting anchor members 40 so arranged that their outer ends occupy the mortar spaces at the ends of the brick and are concealed by the mortar, the inner ends of the anchor members being so constructed as to provide spacers limiting the proximity of the brick to the plates, thereby providing an air space 45 between the brick wall and the assembled plates.

Another object of the invention is the provision 50 of a wall plate providing a plurality of anchor members so constructed as to interlock with the mortar joints of a brick wall built thereabout and to provide keys adapted to prevent relative movement of the wall and the plate after the mortar is set.

Still another object of the invention is the 55 provision of a wall plate providing a plurality of

improved anchor members of the kind described, which is durable, adapted to be economically manufactured, and is satisfactory for its intended purpose. Many other objects and advantages of the construction herein shown and described will be obvious to those skilled in the art from the disclosure herein given.

To this end my invention consists in the novel construction arrangement and combination of parts herein shown and described, and more particularly pointed out in the claims.

In the drawings, wherein like reference characters indicate like or corresponding parts:

Fig. 1 is a perspective view of a fragmentary portion of a wall built about and concealing the 15 anchor members of a plate embodying the principles of the invention;

Fig. 2 is an elevational view of a fragmentary portion of an assembly of wall plates embodying the principles of the invention;

Fig. 3 is a sectional view along the line 3—3 of Fig. 2;

Fig. 4 is a view along the line 4—4 of Fig. 2, drawn to a larger scale;

Figs. 5, 6, 7, and 8 are respectively plan views 25 of modified forms of anchor bars embodying the principles of the invention; and

Fig. 9 is a side elevational view of the anchor bar shown in Fig. 6.

Referring now more particularly to the drawings, the numeral 10 generally designates a plate construction of any suitable material, preferably cast iron or steel and of any desired width and height adapting it as a unit of a wall assembly. Fig. 2 shows in elevation one complete plate 10, 35 and fragmentary portions of contiguous plates providing anchor bars arranged in the positions shown. The assembly comprises a plurality of rows of superimposed plates 10, the height and number of rows being variable in accordance with the required dimensions of a brick wall built about and covering the anchor bars projecting from the plates. All of the plates 10 are shown as of uniform length and width but such dimensions may be varied if desired to adapt the assembly 40 of plates to the dimensions of the brick wall for which the plates provide a backing.

Each plate 10 has an outwardly projecting flange 11 provided with apertures 12, positioned 50 to register with corresponding apertures in the flanges of adjacent plates and adapted to receive bolts or rods for connecting the plates to form an assembly providing a wall of the height and width required for any particular installation. The 55

- plate assembly is shown as providing a vertical wall but may be inclined to the vertical if desired, and the upper flanges of the top plates may be fastened to beams or other members not shown.
- 5 A plurality of triangular shaped web members 13, connecting the plates 10 with the flanges 11, reinforce the plates and prevent warping or cracking. The plates 10 are further reinforced by transversely extending members 14, as shown in
- 10 Figs. 2 and 3.
- The plates 10 are provided with a plurality of anchor bars 15a and 15b projecting perpendicularly from the plates and so positioned as to form vertical and horizontal rows when the plates are
- 15 assembled as shown in Fig. 2. The anchor bars are similar but for convenience in describing their arrangement certain of the bars are designated by numerals 15a and the others by numerals 15b. The anchor bars are shown as of inverted T-shaped cross section, and each is connected with the plate 10 by a boss 16.
- 20 The anchor bars 15a and 15b on the various plates 10 comprising the assembly are so arranged that the bars are adapted to occupy the mortar spaces adjacent the ends of the brick when laid in stretching bond with the brick comprising each horizontal layer breaking joints with brick in each layer next above and below. For this purpose the bars 15a and 15b are so arranged on the
- 25 plates 10 as to provide vertical and horizontal rows. The bars 15a are arranged in vertical rows and are so spaced in the rows as to occupy the mortar spaces adjacent the ends of alternate horizontal layers of brick. The bars 15b are also
- 30 arranged in vertical rows intermediate the vertical rows of bars 15a and are so positioned as to occupy the mortar spaces adjacent the ends of the brick, in the horizontal rows intermediate those in which the bars 15a are positioned.
- 35 40 The lower flat portions 17 of the anchor bars preferably have a thickness slightly less than that of the mortar spaces between the horizontal layers of brick, and the stem portions 18 of the anchor bars have a thickness slightly less
- 45 than that of the vertical mortar spaces between the ends of the contiguous brick. The described construction and arrangement of the anchor bars is such that standard rectangular brick may be utilized to build a wall with brick arranged in
- 50 stretching bond and having alternate horizontal layers breaking joints by positioning the brick with their ends resting upon the laterally projecting portions or members 17. A wall so built will conceal the anchor bars since the bars stop
- 55 short of the exposed face of the brick sufficiently to be completely hidden by the mortar joints.
- 60 It is desirable to provide an air insulating space between plates 10 and the brick wall to minimize the range of temperatures to which the plates are subjected and for this purpose I have provided a boss 16 at the base of each anchor bar. The bosses 16 are adapted as guides for laying the brick and make certain that an air insulating space will be provided by the plates 10 and the
- 65 brick. By laying the brick with their inner edges in contact with the bosses 16 the insulated space will be uniformly of the thickness of the bosses and the exposed surface of the brick will be in alignment. The width of the members 17 and the height of the stems 18 increase outwardly
- 70 from the plates 10 thereby providing keys adapted to lock the brick in the mortar and prevent their movement relative to the plates after the mortar has set.
- 75 Figs. 5 to 9 illustrate modified forms of anchor bars adapted to be embedded in the mortar spaces of brick walls of the kind described. Fig. 5 illustrates the anchor bars as comprising a flat plate 19 adapted to occupy the mortar space between horizontal layers of brick and each connected with the plate 10 by a spacer boss 16. The edges of the plates 19 are of irregular configuration for interlocking with the mortar. Fig. 6, is of the same construction as Fig. 5, with the addition of a stem member 20 shown in elevation 10 in Fig. 9 as increasing in depth outwardly from the plate 10. If desired the stem 20 may be made of substantially uniform depth with its upper edge of irregular configuration to interlock with the mortar.
- 15 Fig. 7 illustrates another form of anchor bar comprising a flat plate 21 having lateral projections 22 at its free end adapted to interlock with the horizontal mortar joints. The construction shown in Fig. 8 is similar to that shown in Fig. 7 and in addition provides a stem member 20 shown in elevation in Fig. 9.
- 20 Thus it will be seen that I have provided an improved wall plate construction and assembly comprising improved anchor bars adapted to occupy the mortar spaces of a lining wall built of brick of standard construction without any modification of sizes or shapes of the brick. The construction is also adapted for use with either vertical or inclined walls and insures the provision 30 of an air insulating space tending to minimize the warping of the plates which otherwise results from the high temperatures to which they are exposed.
- 25 Having thus described my invention, it is obvious that various immaterial modifications may be made in the same without departing from the spirit of my invention; hence I do not wish to be understood as limiting myself to the exact form, construction, arrangement and combination of 35 parts herein shown and described or uses mentioned.
- 30 40 What I claim as new and desire to cover by Letters Patent is:
1. A plate adapted as a backing for a wall built 45 of rectangular brick, and a plurality of anchor bars projecting from the plate at right angles, said bars being angular in cross section and of a thickness adapting them to occupy the mortar spaces between and adjacent the ends of the brick, each 50 of said bars having a boss at its inner end providing a spacer adapted to limit the proximity of the plate and the brick.
2. A plate adapted as a backing for a wall of 55 rectangular brick and arranged in stretching bond, and a plurality of anchor bars projecting from the plate at right angles said bars being adapted to occupy the mortar spaces adjacent the ends of the brick, each of said bars having a boss at its inner end providing a spacer adapted 60 to limit the proximity of the plate and the brick, the transverse cross section of said bars being less at certain selected distances from the plate than at distances more remote therefrom.
3. A plate adapted as a backing for a wall built 65 of rectangular brick, and a plurality of anchor bars projecting from the plate at right angles, said bars being angular in cross section and of a thickness adapting them to occupy the mortar 70 spaces between and adjacent the ends of the brick, each of said bars having a boss at its inner end providing a spacer adapted to limit the proximity of the plate and the brick, the transverse cross section of said bar being less at certain selected 75

distances from the plate than at distances more remote therefrom.

4. An assembly of wall plates of the kind described, each of said plates having a plurality of anchor bars projecting perpendicularly from one side, and a boss connecting each of said anchor bars with its plate, said bars being angular in cross section and of a thickness whereby they are adapted to be contained within the mortar spaces

10 of a wall built of rectangular brick with the inner edges of the brick in contact with said bosses.

5. A plate adapted as a backing for a wall built of rectangular brick, a plurality of anchor bars of inverted T-shaped cross section projecting from one side of the plate arranged in a plurality of laterally extending rows and a plurality of vertically extending rows with the stems of said T sections in vertical alignment, alternate ones of said vertical rows comprising bars positioned only in alternate ones of said lateral rows and the remainder of said vertical rows comprising bars positioned in the lateral rows next adjacent said alternate lateral rows.

6. A plate adapted as a backing for a wall built of rectangular brick, a plurality of anchor bars projecting from one side of the plate arranged in a plurality of equally spaced laterally extending rows and a plurality of equally spaced vertically extending rows, alternate ones of said vertical rows comprising bars positioned in alternate ones of said lateral rows, the remainder of said vertical rows comprising bars positioned in the lateral rows next adjacent said alternate lateral rows, the spacing of said lateral rows being equal to the thickness of a brick plus the thickness of a laterally extending mortar joint, and the spacing of said vertical rows being equal to one-half of the length of a brick plus one-half of the thickness of a vertical mortar joint.

40 7. A plate adapted as a backing for a wall built of rectangular brick, a plurality of anchor bars projecting from one side of the plate arranged in a plurality of equally spaced laterally extending rows and a plurality of equally spaced vertically extending rows, the transverse cross-section of the bars being less at certain selected distances from the plate than at distances more remote therefrom, alternate ones of said vertical rows comprising bars positioned only in alternate ones of said lateral rows, the remainder of said vertical rows comprising bars positioned in the lateral rows next adjacent said alternate lateral rows,

the spacing of said lateral rows being equal to the thickness of a brick plus the thickness of a horizontal mortar joint, the spacing of said vertical rows being equal to one-half of the length of a brick plus one-half of the thickness of a vertical mortar joint. 5

8. A plate adapted as a backing for a wall built of rectangular brick, a plurality of anchor bars projecting from one side of the plate arranged in a plurality of equally spaced laterally extending 10 rows and a plurality of equally spaced vertically extending rows, alternate ones of said vertical rows comprising bars positioned only in alternate ones of said lateral rows, the remainder of said vertical rows comprising bars positioned in the 15 lateral rows next adjacent said alternate lateral rows, the spacing of said lateral rows being equal to the thickness of a brick plus the thickness of a horizontal mortar joint, the spacing of said vertical rows being equal to one-half of the length 20 of a brick plus one-half of the thickness of a vertical mortar joint, the transverse cross-section of the bars being less at certain selected distances from the plate than at distances more remote therefrom, each of said bars having a boss 25 adjacent its juncture point with the plate providing a spacer adapted to limit the proximity of the plate and the brick comprising the wall.

9. A plate adapted as a backing for a wall built of rectangular brick, a plurality of anchor bars 30 projecting from one side of the plate arranged in a plurality of equally spaced laterally extending rows and a plurality of equally spaced vertically extending rows, alternate ones of said vertical rows comprising bars positioned in alternate ones 35 of said lateral rows, the remainder of said vertical rows comprising bars positioned in the lateral rows next adjacent said alternate lateral rows, the spacing of said lateral rows being equal to the thickness of a brick plus the thickness of a 40 horizontal mortar joint, the spacing of said vertical rows being equal to one-half of the length of a brick plus one-half of the thickness of a vertical mortar joint, the cross-section of said bars being of an inverted T-shape, with the stems of the T's 45 of the bars comprised in each vertical row arranged in vertical alignment, the portions of said bars transverse to the stems each being aligned laterally with the corresponding portions of the bars in the same lateral row. 50
